UNITED STATES PATENT OFFICE.

FREDERICK H. CHAFFEE AND WILLIAM E. COLLADAY, OF WASHINGTON, D. C.

DESIGN FOR A MEDAL.

SPECIFICATION forming part of Design No. 15,925, dated March 10, 1885.

Application filed February 4, 1885. Term of patent 3½ years.

To all whom it may concern:

Be it known that we, FREDERICK H. CHAFFEE and WILLIAM E. COLLADAY, citizens of the United States, residing at Washington, in the District of Columbia, have invented and produced a new and original Design for Medals; and we do declare the following to be a full, clear, and exact description of the design, reference being had to the accompanying photographs, and to the letters and figures of reference marked thereon, which form a part of this specification.

Our design is clearly illustrated by the accompanying photographs, of which Figures 1 and 2 represent opposite sides of the medal.

Referring to Fig. 1, the central portion of the medal M is occupied by a representation of a human head in relief. On the opposite side of the medal, as shown in Fig. 2, is a representation, N, of a monument of obeliscal form, being a conventional representation of the National Washington Monument, and below the representation of the monument is portrayed a spread eagle, on each side of which are flags draped from flag-staffs. At the upper part of this side of the medal is a group of

stars, and in the distance, behind the monument, is a landscape view, with the sun represented as partially behind the hills.

We claim—

1. The described and shown design for a medal, the same consisting of a medal having upon its obverse a relief representation of a human head, and upon its reverse a conventional representation of the National Washington Monument, below which is represented a spread eagle and flags and about its top a group of stars. 30

2. The design for a medal, consisting of a circular medal having upon its obverse a relief representation of a human head, and upon its reverse a conventional representation of the National Washington Monument, about the top of which is represented a group of stars, as shown. 40

In testimony whereof we affix our signatures in presence of two witnesses.

FRED. H. CHAFFEE.
WILLIAM E. COLLADAY.
